UNITED STATES PATENT OFFICE.

EDWARD H. LOFTIN, OF NEW YORK, N. Y., ASSIGNOR TO GENERAL RAILWAY SIGNAL COMPANY, OF ROCHESTER, NEW YORK.

CONTINUOUS INDUCTIVE TRAIN-CONTROL SYSTEM.

Application filed December 5, 1925. Serial No. 73,407.

This invention relates to automatic train control and more particularly concerns means for amplifying impulses received from the trackway in a train control system of the 5 continuous inductive type.

In train control systems of the well known continuously inductive type, influences corresponding to traffic conditions are continuously transmitted from the trackway to a 10 moving vehicle, the transmission of such influences being usually accomplished by electro-magnetic induction. As the air-gap through which the electro-magnetic induction must act is necessarily large, and the 15 voltages induced in the car-carried receiving means necessarily small, it is essential to the satisfactory operation of any practical and reliable car-carried control equipment that some form of amplifying means be employed. 20 Such amplifying means must be extremely sensitive, responding to relatively small voltages, must use very little energy in its input circuit, and must be capable of delivering a suitable amount of energy from its output 25 circuit to operate the car-carried control devices.

With the above and other considerations in mind it is proposed in accordance with the present invention to provide a novel type of 30 amplifying means for continuous inductive train control systems, and, more specifically it is proposed to provide amplifying means employing the principle of the electro-static brake for responding to the received impulses and controlling car circuits carrying 35 appreciable currents in accordance with the reception of such impulses.

Other objects, advantages and characteristic features of the invention will become 40 apparent as the description thereof progresses.

In describing the invention in detail, reference will be made to the accompanying drawing in which:—

45 Figure 1 represents in a diagrammatic and simplified manner a typical train control system of the continuous inductive type embodying the amplifying means of the present invention;

50 Figure 2 represents a modified form of amplifying means applied to the car apparatus of a continuous inductive train control system; and

Figure 3 represents a second modification

of the train control amplifying means shown 55 in Figure 1.

Referring first to Figure 1, an extremely simple two-position type of continuous inductive train control system has been chosen for the purpose of illustrating the invention, 60 it being understood that the invention is equally applicable to any other type of continuous inductive train control system.

The trackway apparatus is of the type well known in the art, and requires but little 65 explanation to those familiar with railway signalling and train control practice. The track rails 1 are divided into blocks by the insulating joints 2, the block I and the adjacent ends of the blocks H and J having been 70 shown. The corresponding devices in the several blocks are represented by like reference characters having distinctive exponents. Suitable track relays 3 are connected across the track rails at the entrance ends of the 75 blocks as shown, being normally energized by current from the track batteries 4, connected across the track rails at the exit end of each block. Alternating train control current of a suitable frequency is applied to 80 the two track rails 1 in series by a transformer 5 connecting in series with the track battery 4 at the exit end of each block, the primary winding of this transformer being energized from the transmission line 6 85 through the contacts 7 and 8 of the track relay 3 of the first block in advance. It is evident that the presence of a train in a given block, say the block J, shunts the track circuit and train control current from 90 the track rails 1 behind the train in that block, causing the de-energization of the track relay 3 at the entrance end of the block. The de-energization of this track relay 3 causes the train control current to be 95 cut off from the first block I in the rear of the occupied block by breaking the energizing circuit for the transformer 5 through the contacts 7 and 8.

Wayside signals of the color-light, semaphore or other suitable type may or may not be used in connection with the trackway apparatus of the system, and for the purpose of illustration, the semaphore signals Z have been conventionally shown at the entrance 105 end of each block, their well known operating devices and circuits having been omitted to simplify the disclosure.

A railway vehicle has been conventionally illustrated in the block H by the wheels and axles 9. This vehicle is provided with suitable receiving apparatus which in the present embodiment comprises the receiving coils 10. These coils, which may or may not be provided with laminated iron cores, are connected in such a manner that voltages induced therein by alternating currents flowing in opposite directions in the track rails are additive.

The circuit through the coils 10 is connected as shown to the winding 11 of an electro-mechanical relay R which may take any suitable form, but preferably comprises a laminated U-shaped core structure 12 having a winding 11 thereon and provided with an armature 13 having a reed or contact element 14 soldered or otherwise suitably secured thereto. The armature 13 and the reed 14 are preferably mechanically tuned to resonate at the frequency of the train control alternating current. The circuit through the winding 11 of the relay R is preferably tuned to resonate at the frequency employed by means of a condenser 15.

The amplifying apparatus includes a device generally known as an electro-static brake. It has been found by experiment that if an electrical semi-conductor such as agate, marble, flint, slate, or lithographic stone, having a smooth surface, is inserted between two good electrical conductors such as metallic plates so as to have good surface contact therewith, and if an electrical difference of potential is applied between the metallic plates, there results a strong attraction or adhesion between the semi-conductor and the plates. The adhesion does not occur until good surface contact has been established between both of the conductors and the semi-conductor, and hence can only be utilized to advantage by the use of special apparatus.

One theory which has been advanced in explanation of this phenomenon is as follows. The surface resistance between the conducting plates and the semi-conductor is large in proportion to the internal resistance of the semi-conductor, and for this reason a high electrical tension exists at the point of contact between the plate and the semi-conductor. This high electrical tension or difference in electro-static charge causes the adhesion or attraction between the bodies.

In the embodiment of the invention shown in Fig. 1, the electro-static brake apparatus takes the form of a cylinder 16 of suitable semi-conducting material such as agate, carried on a rotating shaft 17 of low resistance conducting material such as copper or brass. A brake band or strap 18 of thin flexible conducting material such as phosphor-bronze, is held in intimate contact with the surface

of the agate cylinder 16 by the spring 19, the surfaces of the cylinder and of the band being carefully polished to insure as great an area of intimate surface contact as possible. The brake band 18 is connected at one end to the tensioned spring 19 and at the other end to the diaphragm 20 of a suitable sensitive electrical translating device, which in the present embodiment takes the form of a microphone or transmitter T. This transmitter comprises a case 21 of insulating material having a conducting plate 22 supported therein and being filled with a suitable variable resistance substance such as granulated carbon, the arrangement being such that a small variation in the pressure on the conducting diaphragm 20 causes a variation in the resistance of the circuit between the diaphragm 20 and the plate 22. The shaft 17 of the electrostatic brake is continuously rotated by a suitable means such as the electric motor E. It is evident that variations in adhesion between the band 18 and the cylinder 16 caused by variations in potential between the band 18 and the shaft 17 will cause the band to alternately grip and release the cylinder, thus causing vibrations to be transmitted to the microphone or transmitter T which in turn causes variations in the current flow therethrough. It should be noted that the power for moving the diaphragm 20 is supplied by the motor E, the adhesion between the band 18 and the cylinder 16 merely serving to control the application of this power. For this reason the device consumes very little energy.

The transmitter T is connected through a filter circuit to a circuit including a rectifier 23 and a suitable sensitive relay 24 of the direct current type. The rectifier 23 may take any suitable form, and as shown comprises the well known crystal detector. The rectifier may of course be omitted and a suitably sensitive alternating current relay may be used in place of the direct current relay shown.

As the particular train speed or brake control apparatus used forms no part of the present invention, no particular or specific apparatus of this type has been shown. As the initiation of an automatic brake application, a restrictive speed control or the display of an unfavorable cab signal indication is usually accomplished by the de-energization of some suitable electro-magnetic device, the device TC has been shown, it being assumed that the de-energization of this device acts in some suitable manner to restrict the progress of the train or to inform the engineer that unfavorable traffic conditions exist.

Operation; Fig. 1.

The various devices have been shown in

their normal operating positions, that is, the positions assumed when the equipped vehicle is travelling under clear traffic conditions with all circuits and devices properly energized. For convenience, the letters B and C have been used to designate the opposite poles of a suitable source of energy, preferably a storage battery.

Considering first the operation of the sys-

- tem of Fig. 1 under clear traffic conditions, assume that an equipped train is travelling in a clear block, that is, with no other train in the block in which the train under consideration is located or in the first block in advance thereof. Under these conditions, alternating current flows in the track rails in advance of the train, and serves to induce alternating voltages in the receiving coils 10. These voltages are impressed on the winding 11 of the relay R through the tuned receiving circuit including the condenser 15, and as the moving elements of the relay R are mechanically tuned to resonance at the train control frequency, the reed or contact element together with the armature 13 is caused to vibrate, the energy consumption in the receiving circuit being very low by reason of the electrical and mechanical tuning. This vibration of the contact element 14 causes its intermittent contact with the adjustable stationary contact 25, and thus impresses an intermittent or pulsating voltage between the metallic shaft 17 and the band 18 of the electrostatic brake through a partial circuit which may be traced as follows:— from the positive terminal of the battery 26, wire 27, stationary contact 25, contact element 14, armature 13, wire 28, band 18, shaft 17, wire 29 to the negative terminal of battery 26. As explained above, an adhesion occurs between the band 18 and the cylinder 16 causing the band to grip and slip on the cylinder and thus transmitting vibrations to the diaphragm 20 of the transmitter T. The vibration of the diaphragm 20 causes variations in resistance in the circuit through the transmitter, and a pulsating current flows through the transmitter T, the battery 30 and the primary winding of the transformer 31, the circuit being obvious from the drawings. The secondary winding of the transformer 31 is connected through a condenser 32 to the primary winding of a second transformer 33 through a circuit which is obvious from the drawing. This circuit between the transformers 31 and 33 is tuned to resonate at the train control frequency, and acts to filter or choke out undesirable frequencies caused by stray currents in the track rails or in power lines adjacent thereto, or by variations in the friction between the band 18 and a cylinder 16. The alternating current from the transformer 33 is rectified by the rectifier 23 and energizes the relay 24, causing its contact finger 34 to engage its

front contact. With the relay 24 thus energized, the train control device TC is energized through a circuit which is obvious from the drawings. The energization of the device TC prevents the automatic application of the brakes or other automatic restriction, and the train under consideration proceeds through the clear block under the control of the engineer.

When the train under consideration enters a block in which caution traffic conditions exist, that is, the first block in the rear of an occupied block, no train control current flows in the track rails and the relay R does not vibrate. Under these conditions no voltage is applied between the shaft 17 and the band 18 of the electrostatic brake, and the microphone or transmitter T is not actuated, hence the relay 24 and the device TC are de-energized. The de-energization of the train control device TC causes an automatic brake application, a speed restriction or other restrictive control.

As the train under consideration proceeds in an occupied or danger block, the train control current is still cut off from the track rails, and the car-carried apparatus remains in the condition described above in connection with the operation in a caution block. The restrictive control persists, maintaining the train at a safe speed or bringing it to a stop as desired.

In Fig. 2 a modified form of car-carried apparatus has been illustrated. In this modification, a tuned relay 36, identical with the relay R shown in Fig. 1, is employed to vary the potential applied to an electro-static brake. The band 37 of this brake is held in intimate contact with the cylinder 38 thereof by means of two springs 39 and 40 as shown, the band being also directly connected to but electrically insulated from an armature or contact finger 41. The springs 39 and 40 are so proportioned that the contact finger 41 is biased toward the right to the position represented by the dotted line when no potential is applied to the electro-static brake, but is moved into engagement with the two stationary contacts 42 and 43 when the brake is energized. As clearly shown, the contact finger 41 acts directly to control the energization of a train control device TC, closing a circuit to this device when the relay 36 is energized and a potential is applied to the electro-static brake, and opening the circuit to de-energize the device TC when the relay 36 is de-energized. The armature or contact finger 41, the springs 39 and 40 and the brake band 37 in the device of Fig. 2 are preferably designed to have a low natural period of vibration so that these parts will not respond to each interruption in the potential applied to the brake and will thus maintain the contacts 42 and 43 continuously closed. If desired, the continuous operation

of the brake may be obtained by so tuning the armature 44 and the contact reed 45 of the relay 35 that they will not respond to each cycle of the control current, thereby maintaining the contact reed 45 in engagement with its stationary contact 46 so that the potential applied from the battery 47 to the electro-static brake is continuous so long as alternating currents flow in the track rails.

10 It is evident that the operation of the system shown in Fig. 2 under the various traffic conditions is identical with that described above in connection with Figure 1, and for this reason no further detail description of 15 its operation will be given.

In Figure 3, a second modification of the car-carried apparatus has been shown. In this embodiment a different application of the electro-static brake principle is utilized.

20 A block of agate or other semi-conducting material 50 is shaped with a plane surface 51 and a curved surface 52, these surfaces being opposite to each other. A contact plate 53 is secured in intimate contact with 25 the plane surface 51, and a flexible contact strip of conducting material 54 is secured tangent to and in intimate engagement with one end of the curved surface 52, the strip 54 having natural bias away from 30 the curved surface 52 of the semi-conductor to a position represented by the dotted line. Stationary contacts 55 and 56 are provided for engagement by the extended free end of 35 the strip 54 when in its attracted position as shown. When a difference of potential is impressed between the plate 53 and the strip 54, the adhesion between the strip 54 and the semi-conductor 50 causes the band to cling to the curved surface 52, thus moving 40 the strip to the position shown and closing the contacts 55 and 56.

The application of the embodiment shown in Fig. 3 to the car-carried apparatus of a train control system is clearly evident from 45 the drawing. A sensitive electro-mechanical relay 57 is provided, being energized by the impulses received from the trackway, and acts to apply a potential from the battery 58 to the plate 53 and the strip 54, causing 50 the contacts 55 and 56 to be closed and the train control device TC to be energized under favorable traffic conditions. When no 55 train control currents flow in the track rails the relay 57 is de-energized and the potential is cut off from the electro-static device, thus permitting the strip 54 to assume its de-energizing position as shown by the dotted line, and de-energizing the train control device TC, thus causing a restrictive control. The 60 armature 59 and the contact reed 60 of the relay 57 used in the embodiment shown in Fig. 3 are suitably constructed to have a low natural period of vibration so that the potential from the battery 58 will be 65 stably applied to the electro-static device

while the train control impulses are being received.

From the above description it is seen that a very simple and inexpensive amplifying means for use in connection with automatic train control systems has been devised. This amplifying means employs the electro-static brake principle in which appreciable currents may be controlled by very slight variations in voltage, which condition is very 75 desirable in a train control system.

As the present invention has been described in a rather specific manner and in connection with certain specific devices and circuits, it should be clearly understood that 80 certain changes, combinations and modifications may be made without departing from the scope of the invention as defined by the appended claims.

What it is desired to secure by Letters 85 Patent is:—

1. In an automatic train control system, means for inductively transmitting influences from the trackway to a moving vehicle, amplifying means comprising a relay 90 normally energized by said transmitted influences, an electro-static brake device controlled by said relay and means for controlling the progress of the vehicle by said electro-static brake device. 95

2. In an automatic train control system, trackway means for transmitting influences to a moving vehicle, car-carried means for receiving said influences while the vehicle is in motion, means for amplifying said influences including an electro-static device and train control means controlled by said electro-static device. 100

3. In an automatic train control system, car-carried apparatus comprising a receiving circuit for inductively receiving influences transmitted from the trackway, a relay connected in said circuit and having a vibratory member, a stationary contact adapted to be engaged by said vibratory member when said influences are received, a source of potential controlled by said vibratory member and said contact, and an electro-static device controlled by said controlled source of potential. 105

4. In an automatic train control system, car-carried apparatus comprising, a receiving circuit adapted to receive influences transmitted from the trackway, a relay in said circuit having a vibratory member, a second circuit including said vibratory member, a contact and a source of potential in series, and an electro-static device in said second circuit adapted to be operated by said source of potential and to be controlled by said vibratory member and said contact. 120

5. In an automatic train control system, car-carried apparatus comprising a relay having a vibratory contact member, receiving means for operating said relay in ac- 125

cordance with influences transmitted from the trackway, a source of potential controlled by said vibratory contact member, and an electro-static device including a conducting element and a semi-conducting element, adapted to be operated by said controlled source of potential.

6. In an automatic train control system, trackway means for transmitting influences to a moving vehicle, a car-carried control device for controlling the progress of the vehicle, and car-carried means for amplifying said influences comprising, a relay operated by said influences, a circuit including a source of potential controlled by said relay, two conducting members adjacent to and in engagement with a semi-conducting member, said conducting members being connected to said controlled source of potential, and means for controlling the operation of said control device by one of said conducting members.

7. In an automatic train control system, a car-carried receiving circuit, trackway means for energizing said circuit with currents of pre-determined frequency, and car-carried apparatus comprising, a relay energized by said receiving circuit and having a vibratory contact system which is mechanically tuned to resonate at said pre-determined frequency, a source of potential controlled by said vibratory contact system, an electro-static relay including a conducting element and a semi-conducting element adapted to be operated by said controlled source of potential, and train control means governed by said electro-static relay.

8. In an amplifying system, a receiving circuit, a vibratory relay connected in said receiving circuit, a source of potential controlled by said vibratory relay, an electro-static device operated by said controlled source of potential, and means for controlling a circuit by said electro-static device.

45 9. In an amplifying system, a receiving circuit, a relay energized by currents in said receiving circuit and having a vibratory contact system tuned to resonate at a pre-determined frequency, a source of potential controlled by said vibratory contact system and an electro-static device including a conductor and a semi-conductor governed by said controlled source of potential.

55 10. In an automatic train control system, an inductive car-carried receiving circuit, trackway means for inducing currents in said receiving circuit, car-carried apparatus including a relay energized by said receiving circuit, a mechanically tuned vibratory contact on said relay, an electro-static device comprising a semi-conducting element in intimate contact with two conducting elements, a source of potential controlled by said vibratory contact and applied to said conducting elements, and means for control-

ling a train control device by one of said conducting elements.

11. In an automatic train control system, an inductive car-carried receiving circuit electrically tuned to resonate at a predetermined frequency, trackway means for inducing currents of said frequency in said receiving circuit under favorable traffic conditions only, car-carried apparatus including a relay energized by said receiving circuit, said relay having a vibratory contact mechanism tuned to resonate at said predetermined frequency, an electro-static device comprising a semi-conductor and a plurality of conductors, a source of potential controlled by said vibratory contacts and applied to said conductors, and a train control device controlled by one of said conductors.

12. In an automatic control system, an inductive receiving circuit, trackway means for inducing currents in said receiving circuit, car-carried apparatus comprising a relay connected in series with said receiving circuit, a contact controlled by said relay, an electro-static device comprising a movable semi-conducting element in intimate contact with a plurality of conducting elements, means for continuously moving said semi-conducting element, a source of potential applied to said conducting elements in accordance with the operation of said relay contact, and means for governing the operation of a train control device in accordance with the motion of one of said conducting elements.

13. In an automatic control system, an inductive receiving circuit, trackway means for inducing currents in said receiving circuit, car-carried apparatus comprising a relay connected in series with said receiving circuit, a vibratory contact controlled by said relay, an electro-static translating device comprising a movable semi-conducting element, a movable conducting element rigidly connected to and in intimate contact with said semi-conducting element and a second movable conducting element in intimate contact with said semi-conducting element, means for continuously moving said semi-conducting element and said rigidly connected conducting element, a source of electrical potential, means including said vibratory contact for applying said source of potential between said conducting elements

110 145 110 115 120 125 130

of said electro-static device whereby said second movable conducting element is moved by said semi-conducting element, and means for controlling a train control device in accordance with the motion of said second movable conducting element.

14. In an automatic control system, an inductive receiving circuit, trackway means for inducing currents in said receiving circuit, car-carried apparatus comprising a relay connected in series with said receiving

6

circuit, a vibratory contact controlled by said relay and tuned to resonate at a predetermined frequency, an electro-static device comprising a semi-conductor rotatably mounted on a conducting shaft, means for continuously rotating said shaft and said semi-conductor, a movable conducting element in intimate contact with said semi-conductor, a source of electrical potential applied between said conducting shaft and said conducting element, said potential being controlled in accordance with the vibration of said vibratory element, whereby said conducting element is moved by said semi-conducting element, and means for governing the operation of vehicle control apparatus in accordance with the movement of said conducting element.

15. In an automatic control system, an inductive car-carried receiving circuit tuned to resonate at a predetermined frequency, trackway means for inducing voltages of said predetermined frequency in said receiving circuit under favorable traffic conditions only, 20 car-carried apparatus comprising a relay connected in said receiving circuit, a vibratory contact operated by said relay and mechanically tuned to resonate at said predetermined frequency, an electro-static device comprising a semi-conducting element mounted on a conducting shaft, means for continuously rotating said shaft and said semi-conductor, a conducting element biased into intimate contact with said semi-conductor, means including a source of electrical potential and said vibratory contact for applying a difference of potential between said conducting shaft and said conducting element in accordance with said predetermined 25 frequency, whereby said conducting element is moved at said predetermined frequency by said semi-conducting element, vehicle control means acting when energized to prevent a restrictive control and means whereby said control means is energized when said conducting element is moved at said predetermined frequency.

16. In an automatic train control system, trackway means for transmitting influences to a moving vehicle, car-carried means for receiving said influences while the vehicle is in motion, means for amplifying said influences including a device responsive to electro-static forces, and train control means controlled by said device.

17. In an automatic train control system,

trackway means for transmitting influences to a moving vehicle, car-carried means for receiving said influences while the vehicle is in motion, means for amplifying said influences including a mechanically driven device controlled in accordance with electro-static influences impressed thereon, and train control means controlled by said device.

18. In an automatic train control system, 60 car-carried apparatus comprising a receiving circuit for inductively receiving influences transmitted from the trackway, a relay connected in said circuit and having a vibratory member, a stationary contact adapted to be 65 engaged by said vibratory member when said influences are received, a source of potential controlled by said vibratory member and said contact, and a driven electro-static device controlled by said controlled source 70 of potential.

19. In an automatic train control system, 75 car-carried apparatus comprising a receiving circuit for inductively receiving influences transmitted from the trackway, a relay connected in said circuit and having a vibratory member, a stationary contact adapted to be 80 engaged by said vibratory member when said influences are received, a source of potential controlled by said vibratory member and said contact, and a device responsive to, 85 and having means for impressing thereon, electrostatic forces, controlled by said controlled source of potential.

20. In an automatic train control system, 90 car-carried apparatus comprising, a receiving circuit adapted to receive influences transmitted from the trackway, a relay in said circuit having a vibratory member, a second circuit including said vibratory member, a contact and a source of potential in series, and a device, controlled by static electrical forces, in said second circuit adapted 95 to be operated by said source of potential and to be controlled by said vibratory member and said contact.

21. In an amplifying system, a receiving circuit, a vibratory relay connected in said receiving circuit, a source of potential controlled by said vibratory relay, a device responsive to electro-static forces, operated by said controlled source of potential, and means for controlling a circuit by said electro-static device.

In testimony whereof I affix my signature.

EDWARD H. LOFTIN.
